(57) **CLAIM**

The ornamental design for a hood ornament, as shown and described.

DESCRIPTION

FIG. 1 is a perspective view of a tractor-trailer showing the hood ornament of our new design;

FIG. 2 is a perspective view of the hood ornament;

FIG. 3 is a top view of the hood ornament;

FIG. 4 is a front view of the hood ornament;

FIG. 5 is a left side view of the hood ornament, the opposite side view being a mirror image of that shown; and,

FIG. 6 is a rear view of the hood ornament.

The bottom of the hood ornament is unornamented.

The broken line showing of a vehicle, in FIG. 1, depicts environment and is not part of the claimed design.

The hood ornament is shown on an enlarged scale in FIGS. 2-6.
